ATTORNEY

UNITED STATES PATENT OFFICE.

FELIX J. COUGHLIN, OF VERSAILLES, OHIO.

PARACHUTE.

1,387,455.

Specification of Letters Patent. Patented Aug. 16, 1921.

Application filed April 30, 1919. Serial No. 293,858.

To all whom it may concern:

Be it known that I, FELIX J. COUGHLIN, a citizen of the United States, residing at Versailles, in the county of Darke and State 5 of Ohio, have invented certain new and useful Improvements in Parachutes, of which the following is a specification.

Modern practice compels that parachutes be packed in small compass in receptacles 10 usually water-tight. They must open automatically and with certainty and no special skill should be required to pack them in their receptacles in such a manner that their opening when needed will not be interfered with. 15 The embarkation in the parachute is necessarily hurried in most instances, so that a parachute must be designed free from any possibility of the numerous necessary ropes fouling from the sail failing to extend, or 20 from any defect in the automatic opening of the parachute that would prevent it from taking its proper form, without any interference by the operator who, under the stress and danger necessarily incident at the time 25 of his embarkation, is not in a condition to exercise any thought or skill. Besides meeting these requirements, the present device has many features of strength, stability and adaptability that will appear from reading 30 the following portion of this specification.

Figure 1 is a side elevation of a parachute opened for descent. Fig. 2 is a side elevation of a parachute just after its detachment from its fastening. Fig. 3 is a side elevation 35 of a parachute beginning to leave its receptacle. Fig. 4 is a view of the tunnel looking at it from the bottom. Fig. 5 is a view of the parachute as shown in Fig. 2 looked at from the top. Fig. 6 is a view of the 40 parachute packed in its receptacle. Fig. 7 is a view of the load ring and sling for the aviator looking at the parachute open from the bottom. Fig. 8 shows the connection between the gromet and the suspension 45 cords. Fig. 9 is a top view of the parachute opened. Fig. 10 is a bottom view of the hoops of the air tunnel nested together. Fig. 11 shows the top of the parachute immediately before being detached from the 50 packing case. Fig. 12 is a slightly different form of parachute just detached from the packing case. Fig. 13 is a perspective view of the air tunnel, gromet with connecting guys, and Fig. 14 a form of seam that may 55 be used to unite the sail gores. Fig. 15 shows a modified form in open position.

The parachute has a sail, 5, from which, when the parachute is open and descending, is hung the load ring, 13, by the suspension cords, 4, 4. A collapsible air tunnel to secure the carrying of the air into the interior of the sail to open it freely and evenly, is suspended from the top of the sail and attached by guys, 1, to the load ring, 13. The sail of the parachute is formed of gores, 60 21, connected together at their edges by the seams, 20. At the top of the parachute is the re-inforce, 6. The gromet, 12, surrounds the vent, 14. The suspension cords, 4, 4, are attached to the gromet, 12, in practice, by 65 splices, 17. See Fig. 8. The suspension cords, 4, 4, are preferably each in a single piece from the gromet, 12, to the load ring, 13, and pass through the seams, 20. The load ring, 13 and the gromet, 12, are connected by guys that are enough shorter than 70 the total length between the gromet and load ring of the suspension cords, 4, 4, to bring these guys taut between the load ring, 13, and the gromet, 12, before any of the 75 weight of the load is upon the sail of the parachute. In practice, these guys extend the air tunnel also; one set of guys running from the load rings, 13, to the bottom frame, 10, of the air tunnel, the other set from the 80 top frame, 8, of the air tunnel to the gromet, 12. The top frame, 8, and the lower frame, 10, of the air tunnel are connected by collapsible connections, in practice, the netting, 9. This netting, 9, is preferable to any 85 other form of connection I know, because it prevents better than any other I have tried, the fouling of the guys or suspension cords. The air tunnel preferably has also intermediate hoops, 81, and 82, and is suspended at a short distance below the top of 90 the parachute. The guys, 1, 1, and 2, 2, and the netting, 9, should, while the sail is opening at least, be rendered taut by the load. The frames, 8, and 10, are preferably 95 circular. I prefer to wrap them with tapes, 17, to prevent them from cutting the silk or other fabric of the sail. The hanger, 15, is supplied for attachment of the parachute to the packing case, 20, by the holder, 50, attached to face, 51, of this case. It is 100 preferably attached by the thin cords, 52.

The parachute when carried upon the airplane or balloon is packed inside a packing case, 20. The one illustrated is a convenient 110 form in that it is circular and flat on the opposite sides. The case should, of course,

be as small as possible to contain the bulk of the parachute and in this respect the present parachute in which every part is collapsible fulfills a very important requirement. While the packing is being done with some care in order to get the entire bulk of the parachute inside the packing case, I have found that in practice the troubles incident to the necessity with the 5 ordinary form of parachute of careful packing so that it will open with certainty are rendered unnecessary in the present device, which will open practically without regard to the manner in which it is packed. The 10 sling, 7, should project outside the bottom of the packing case. In Fig. 3 the parachute is shown just emerging from the packing case, 20. The guys, 1, 1, between the 15 load ring, 13, and the bottom frame, 10, of the air tunnel are taut, and have drawn this 20 frame down and make the meshing between the frames of the tunnel begin to take its tubular form. The parachute then passes into the appearance shown in Fig. 2. The 25 guys, 2, between the upper frame, 8, and the gromet, 12, and the meshing, 9, between the frames, 8, and 10, have become taut and have caused the hanger, 15, to break the 30 cords fastening it to the packing case and the 35 parachute is descending freely. It may be noted that the suspension distance of the 40 tunnel is sufficient to insure the passage of a column of air into the interior of the sail, 5, and this will not be pulled down by the 45 suspension cords, 4, 4, which will remain loose as though carrying no weight and have not taken any part in detaching the 50 parachute from its moorings. The 55 parachute will finally take the form shown in Figs. 1 and 9, and the sail will have all its 60 carrying capacity in effect. A load bar or other load carrier can of course replace the 65 load ring, 13. Figs. 12 and 15 show a form of parachute where the air tunnel is hung 70 lower down and contains only two hoops.

I claim:

1. In a parachute, the combination with the sail having a vent and a load carrier, of readily frangible sail supporting cords, flexible connections between the middle part of the sail and the load carrier and an air tunnel collapsible in the direction of its length, and extended by the tautening of the flexible connections secured between the load ring 55 and the top of the sail.

2. In a parachute, the combination with

the sail having a vent, and a load carrier, of readily frangible sail supporting cords, flexible connections between the middle part of the sail and the load carrier and an air tunnel collapsible in the direction of its length, and extended by the tautening of the flexible connections, the tunnel having its suspension position between the vent and the load carrier. 60

3. In a parachute, the combination with the sail and load carrier of a collapsible air tunnel, having an upper and a lower frame and flexible connections between the frames, and guys connecting the upper frame to the 65 middle portion of the sail, and guys connecting the lower frame to the load carrier, the combined lengths of the guys and flexible connections between the frames of the air tunnel being short enough to extend the air 70 tunnel before weight is thrown on the 75 parachute.

4. In a parachute, the combination with the gromet, and the load carrier, of a collapsible air tunnel having an upper and 80 a lower frame connected together with a porous textile fabric, and guys extending from the upper frame of the tunnel to the gromet and from the lower frame of the 85 tunnel to the load carrier the combined length of the guys and porous textile fabric between the said frames being short enough to extend the air tunnel before weight is thrown on the parachute, and a hanger connected to said gromet. 90

5. In a parachute, the combination with the sail and load carrier of readily frangible connecting cords secured to the sail near its center, an air tunnel, having frames with 95 flexible connections between the frames, and guys connecting the upper frame to the middle portion of the sail structure, and the lower frame to the load ring and guys extending from the bottom frame of the air 100 tunnel to the load ring, the guys and flexible connections being short enough to extend the tunnel before weight is thrown on the 105 parachute sail.

6. The combination, in a parachute with a sail and load carrier of readily frangible 110 supporting cords and flexible connections supporting an air tunnel and extending between the middle portion of the sail and the load carrier.

In testimony whereof I affix my signature.

FELIX J. COUGHLIN.
